UNITED STATES PATENT OFFICE.

HARRY BENSON CRANAGE, OF KIRKSTALL, LEEDS, ENGLAND, ASSIGNOR OF FOUR-TENTHS TO LOUIS FOX, OF LEEDS, ENGLAND.

IRONING-MACHINE FOR PRESSING THE SEAMS OF CLOTHING.

1,356,044.

Specification of Letters Patent. Patented Oct. 19, 1920.

Application filed January 5, 1917. Serial No. 140,691.

To all whom it may concern:

Be it known that I, HARRY BENSON CRANAGE, of 20 Vicarage avenue, Kirkstall Lane, Kirkstall, Leeds, in the county of York, England, engineer, have invented new and useful Improvements in or Relating to Ironing-Machines for Pressing the Seams of Clothing, of which the following is a specification.

10 This invention relates to that type of ironing machine used for pressing the seams of garments in which the seam is first opened and afterward pressed.

Hitherto in this kind of machine it has 15 been customary for the operator to place the work in position and move the iron across the same, and at the same time has had to put the necessary pressure upon the iron. By the above mentioned method the 20 pressure is unequal and the operator is liable to become tired after working the machine for some time and then the pressure consequently becomes weaker.

The object of this invention is to provide 25 means or apparatus which is effective in automatically moving the work beneath the pressing iron and at the same time puts the necessary pressure upon the same, and as far as possible reduces the strain upon the operator to a minimum.

In the drawings hereunto annexed are shown three methods of carrying the invention into practice, two of which are in the vertical form with the feeding device arranged respectively above and below the work, and the horizontal form of framework with the feeding device below the work.

Figure 1 is a side elevation of the pressing mechanism arranged in the vertical form with the feeding device above the work support;

Fig. 2 a front elevation of the same machine;

Fig. 3 a back elevation of the same;

45 Fig. 4 a part plan of the machine looking at the top;

Fig. 5 is an enlarged side elevation of the pressing iron;

Fig. 6 an end elevation of the same;

50 Fig. 7 a plan of Fig. 6 looking at the top;

Fig. 8 is an elevation of a machine with vertical framework with the feeding device below the work and actuated by means of

vertical and horizontal shafts and bevel or miter gearing;

Fig. 9 a part plan of Fig. 8;

Fig. 10 is an enlarged section of the work support and under feed shown at Fig. 8;

Fig. 11 is an enlarged transverse section of the work support;

Fig. 12 an enlarged sectional plan of the work support shown at Fig. 8;

Fig. 13 an enlarged plan of the work support shown at Fig. 8 looking at the top;

Fig. 14 a side elevation of a machine with a horizontal frame with the feeding device arranged below the work;

Fig. 15 a front elevation of the machine shown at Fig. 14;

Fig. 16 a back elevation of the same machine;

Fig. 17 a modified form of attaching the feeding device to the operating mechanism;

Fig. 18 a plan of Fig. 17.

Like parts in all the views are marked with similar letters of reference.

The vertical form of machine with the feed respectively above and below the work will be first described and afterward the horizontal form shown at Figs. 14 to 16.

At Figs. 1 to 7, *a* is the standard of the machine which forms part of, or is fixed to, a square or other shaped base plate *b*. The standard *a* is made of any suitable size and shape and it is provided with two vertical arms *a*¹, *a*², which project in an upward direction from the stem portion *a*³ and a suitable space *a*³ is provided between the two arms for the reception of the work to be operated upon. The arms are made of different lengths; that is to say, arm *a*¹ is shorter in length than the rear arm *a*². The upper portion of the arm *a*¹ is arranged to form a vertical circular bearing for the reception of the spindle *c* upon which the hollow work support *e* is fixed or forms a part.

The work support may be of any suitable and desired shape, as, for example, rectangular, as shown in the drawings.

At a suitable distance from the top of the vertical bearing on one or on opposite sides thereof is or are provided a slot hole or slot holes *f* of any suitable length to permit of the work support being drawn in a downward direction. Through the slot holes *f* and spindle *c* is passed a pin or projection *g*

- for preventing the spindle from turning in its bearing. The vertical hole in the bearing is made of such a length as to permit of a coiled spring *h* being inserted therein below the bottom of the spindle *c*, and in the lower portion of the bearing is formed a second vertical hole *i* through which passes a rod or spindle *j* which is screwed or otherwise fixed into the bottom of the spindle *c*.
- 10 The lower end of the rod projects beyond the vertical bearing into a slot hole *k* provided in the web portion *a⁴* of the vertical arm *a¹* below the upper portion thereof which forms a bearing for the spindle *c*.
- 15 By arranging the lower end of the rod *j* to project into the slot *k* the rod *j* can be readily connected by a rod or bar *l* to a treadle *m* fulcrumed at *n* to the stem *a* of the vertical frame. By this means a direct
- 20 vertical pull is imparted to the spindle *c*. The treadle *m* is provided with a projecting lever portion *o* beyond the fulcrum *n* which is arranged to pass through a slot hole *p* in the strengthening web portion *a⁵* of the
- 25 stem *a*. The projecting lever portion *o* is connected by a rod *q* to a belt shipping arrangement *r* fulcrumed on a pin *s* carried by a bracket *t* fixed to the web portion of the arm *a²*. To the web portion *a⁵* is
- 30 fixed, so as to project outwardly in front of the machine and also a suitable distance on each side of the said web, a bracket *u* which forms a table for receiving the work to be operated upon and for preventing it
- 35 from being placed on the floor.

The rear arm *a²* of the framework is bifurcated at its top *a⁶* for receiving the operating mechanism to be presently described. The portions of each of the bifurcations or arms are arranged to be curved and carried forward partially over the space *a³* between the two arms of the framework, as shown at Fig. 1. In the bifurcated head of the machine are provided

40 bearings for the driving shaft *v* and for the double ended lever *w* to which the pressing iron *x* is connected. The double ended lever *w* is mounted upon a spindle *y*. A bearing is also formed for a fork *z* which is employed for operating the feeding device 1.

On the driving shaft *v* are mounted outside the bifurcated head *a⁶* the fast and loose pulleys *2*, *2^a*, and between the bifurcations of the head *a⁶* are mounted on the same shaft a pair of cams *3*, *4*, for operating respectively the rear end of the double ended lever *w* which reciprocates the pressing iron *x* and the forked lever *z*. The forked lever *z* is mounted upon the spindle 5. The fast pulley *2* is also arranged, when required, to form a fly wheel. The cams *3* and *4* are either formed separately or connected together. Cam *3* is arranged to act upon a roll or runner *6* mounted in the bifurcated end *7* of a spindle *9* carried in

the rear end of the double ended lever *w* and a coiled spring *8* is also inserted in a recess,—formed for its reception in the said end,—for keeping the runner *6* in contact with the perimeter of the cam. The spindle 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 18^e, one end of which is fixed to the framework of the machine. The rod 18 is prevented from falling when the work support *e* is depressed by an adjustable bracket 18^a being secured to the framework.

5 Between the bifurcations of the head portion *a*⁶ of the standard or framework is arranged a spindle 20 on which are formed or fixed two projecting arms 21 and 22 arranged 10 at a suitable angle to each other. The vertical arm 21 is connected at its upper end by a coiled spring 23 to a pin or stud 24 fixed to one of the curved bifurcated portions of the head *a*⁶. The arm 22 is 15 provided at its outer end with a roll or runner 25 which operates upon the upper surface of one of the rods 18 to which the feeding frame is attached. By this means the feeding frame is kept down upon the work,— 20 and against the pressure of spring *h*,—but at the same time can be readily raised for passing the work between the top of the work support *e* and the serrations of its feeding device.

25 In the drawings one treadle *m* is shown for both opening the work support and operating the belt shipping arrangement, but it is to be clearly understood that if so desired separate treadles may be employed for 30 the above named purpose, or the lever portion *o* may be mounted upon the same spindle *n* as that upon which the treadle *m* is pivoted or fixed, but at a distance therefrom so as to be separate from the treadle. In all 35 cases the treadles are arranged at a suitable distance below the work table or bracket *u*.

The action of the above described machine is as follows:—

40 The belt 26,—shown in dotted lines at Fig. 2,—is connected with a shaft,—not shown in the drawings,—which receives its rotary motion from any suitable source of power and when the machine is at rest will be upon the loose pulley 2^a. The operator 45 by means of treadle *m*, connecting rod 1, spindles *j* and *c* draws down the work support *e* a sufficient distance to permit of the seam to be opened and pressed to be placed on the top of the work support *e*,—which 50 may or may not be heated by any suitable means,—and under the feeding device 1. The pressing iron *z* will then be in a slightly raised position. On the treadle rising it will carry the work to be operated upon into 55 contact with the serrated undersurface of the feeding frame and on the belt shipping motion *r* moving the belt 26 on to the fast pulley 2 a rotary motion will be imparted to the driving shaft *v* and cams 3 and 4 which 60 will lower the iron on to the open seam and will press it, and by the timing of the cam 3 it will also slightly raise the iron for releasing the pressure thereon after each pressing operation, and as soon as the pressure 65 is relieved the fork *z* will, by the ac-

tion of the cam 4 thereon, have drawn the feeding frame 1 a sufficient distance to the rear of the work support *e* and will automatically commence to move forward for opening a fresh portion of the seam ready 70 for the descent and pressing action of the iron.

It will readily be understood that no movement in a horizontal direction is imparted to the pressing iron *z* but only a rising and falling motion is imparted thereto by the double ended lever *w* when acted upon by cam 3. The pressure on the pressing face of the iron can be regulated by the milled headed adjusting nut 10 and screw 75 threaded spindle 9 which raises or lowers the rear end of lever *w* as may be required. The operation of first opening the seam and then pressing it, and again slightly releasing the pressure of the iron to permit of the 80 feeding operation taking place, is repeated until the whole of the seam has been opened and pressed.

At Figs. 8 to 13 are shown modifications 90 in the above described vertical machine which consist in arranging the feed below the work and imparting the requisite motion thereto by means of two vertical and one horizontal shafts and gearing. In this arrangement the fork *z* and feeding frame 95 1 are dispensed with, and in place thereof a feeding device 27 constructed somewhat on the same lines as the feeding foot of a sewing machine is mounted and arranged to work within the hollow work support *e*. 100 The upper surface of the feeding device is provided with two rows of serrations 28 and to two of its sides are screwed the projecting studs 29 upon which are mounted the dies or blocks 30 which work in the inclined 105 slots 31 formed in two opposite sides of the work support *e*.

It will readily be understood that in this arrangement the work support *e* is provided with a rectangular opening 32 in which the feeding device 27 is made to work. In the feeding device is formed a rectangular recess 33 in which is arranged to work a cam 34 provided with a flange 35. The cam 34 is made of such a depth as to permit of the feeding device 27 rising and falling thereon as the die or block 30 moves in the angular slot 31.

A rotary motion is imparted to the cam 34 120 from the driving shaft *v* through bevel gearing 36, vertical shaft 37, gearing 38, horizontal shaft 39, gearing 40, 41, vertical shaft 42. The shafts 37 and 39 are carried in bearings 43, 44 formed for their reception on the stem or standard *a*, and the lower end of shaft 42 slides in bearings formed for its reception in the boss 45 of wheel 40 which is mounted in bearings 44^a of the stem or standard *a*. The boss of this wheel is provided with a collar 46 to permit of it being 125 130

retained in its proper position and also for the shaft 42 to slide through it when the treadle *n* is depressed for withdrawing the work support *e* out of contact with the pressing iron *x*.

It will readily be understood that the shaft 42 is provided with either a keyway or a spline to permit of the sliding motion taking place and also for a rotary motion 10 to be imparted to the cam 34. The rod *l* in this instance is connected to a plate 47 which is secured to the spindle at or near its bottom. On motion being given from the driving shaft *v* through the gearing, vertical 15 and horizontal shafts to the cam 34 as the latter rotates it imparts a reciprocating motion to the feeding device 27 and as the said device is reciprocated the block 30 is caused to move up or down for causing the feeding 20 device to rise or fall. That is to say, when the serrations of the feeding device are in engagement with the cloth and are being moved by the cam toward the driving shaft *v* the feeding takes place, but on the return 25 of the block to the front of the machine the blocks 30 will descend in the inclined grooves thereby withdrawing the serrations 28 below the upper surface of the work support *e*. This movement of the feeding device is similar to that of the feed dog of a 30 sewing machine. In this instance the cam 4 is dispensed with and the cam 3 acts upon the roll or runner 6 as previously described.

Other parts of the machine are of a similar 35 description and operate in a similar manner to that described for Figs. 1 to 7.

At Figs. 14 to 16 is shown another form 40 of under feed in which the framework of the machine is arranged in a horizontal position. The horizontal arms of the framework 48 and 49 take the place of the arms *a*¹, and *a*² of the machine shown where a vertical framework is employed. In this case the feeding device consists of a dog or 45 fixing 50 and is provided with serrations 51 on its upper surface. The feed dog is jointed to a lever 52, one end of which is connected to the projection 19 of the forked lever *z*. The lever 52 is jointed in a suitable position 50 to a rocking lever 53 at a suitable distance from the projection 19. Lever 53 is fulcrumed at 54 to the arm 49 of the framework.

On motion being imparted by cam 4 on 55 driving shaft *v* to the forked lever *z* the feed dog 50 will move outward,—that is, to the left hand of Fig. 14,—and by the bar 52 being attached to the rocking lever 53 it will be carried below the surface of the work 60 support portion 55 of the arm 49, but on the movement of the feed dog 50 and bar 52 in an opposite direction the rocking lever causes them to rise for bringing the serrations 51 above the level of the work support 65 55 for feeding purposes.

Other parts of the machine, except that the arms are arranged in a horizontal position and the frame work is adapted to be fixed upon a bench, and with a rising and falling work support and treadles for operating the 70 same, are dispensed with, are of a similar construction to and are operated as described for Figs. 1 to 6.

In both of the herein described machines,—shown at Figs. 8 to 16,—provided 75 with an under feed the nose or point of the pressing iron *x* is employed for opening the seam, and in order to permit of this being done the pressure on the iron is slightly released so as to permit the material to be 80 automatically fed along and the seam to be opened at the pointed end of the iron.

The work support *e* may be heated, when required,—though not necessarily so,—by any convenient means, such as electricity, 85 gas, or heated oil, or the like.

No claim is herein made to the specific structure of the embodiment of the invention illustrated in Figs. 8 to 13, inclusive, as the same forms the subject matter of a 90 divisional application filed September 8, 1920, Serial No. 408,991.

What I claim is:—

1. A machine for opening and pressing the seams of garments characterized by 95 framework having two arms of different lengths, one of which is employed for supporting the work to be operated upon and the other is bifurcated and carries the operating mechanism, said operating mechanism comprising a heated pressing iron, a double ended lever pivoted to the framework and jointed at one end to the pressing iron, a feeding device for opening the seams of the garments and means for separately operating the feeding device and pressing iron whereby after the work has been placed in position the seam is automatically opened during the feeding operation and afterward pressed.

2. In a machine of the class described, a framework having two arms of different lengths with a space between them, one of said arms being arranged as a work support, and the other arm being bifurcated to partially pass over and bridge the space between the arms, a heated pressing iron, a double ended lever pivoted to the bifurcated arm of the machine, the pressing iron being jointed at one end to the said lever and the opposite end of the lever being provided with a spring controlled bifurcated pin, said pin carrying a roll at its lower end and mechanism contacting with the roll for operating the said lever, as and for the purposes set forth.

3. In a machine of the class described, the combination of framework having two arms of different lengths with a space between them, one of said arms being arranged as a 13

work support, the other arm being bifurcated at its top and arranged to partially pass over and bridge the space between the arms, a work support adapted to be carried 5 by one of the arms of the framework, means for raising and lowering the work support to and from its work, a feeding device working in connection with the work support and having one of its surfaces serrated, 10 a heated pressing iron arranged above the work support, a double ended lever pivoted to the bifurcated portion of the framework, one end of the said lever being jointed to the pressing iron and its opposite end carrying a spring controlled spindle, said spindle being bifurcated at its lower end, a roll mounted in the bifurcated end of the spindle and means for operating the feeding device and means acting on the roll to operate the 15 20 pressing iron as and for the purposes set forth.

4. In a machine of the class described, the combination of framework having two arms of different lengths with a space between 25 them, one of said arms being adapted as a work support, a feeding device arranged to work within the work support, means for raising, lowering and reciprocating the feeding device independently of the pressing 30 iron, a pressing iron and means for heating it, a double ended spring controlled lever, one end of which is jointed to the pressing iron and its opposite end is provided with a spring controlled adjustable spindle having 35 a bifurcated end and means for oscillating

the double ended lever as and for the purposes set forth.

5. A machine for the purpose described having in combination a support for the garment to be pressed, a heated pressing iron, 40 means for effecting relative vertical movement between the support and iron, and means for automatically feeding the garment between the support and iron and opening the seam to be pressed when said 45 parts are separated.

6. In a machine of the class described, the combination of a standard having two arms of different lengths with a space or gap between them, one of said arms being 50 adapted to receive a work support and the other arm being bifurcated at its top and arranged to partially bridge the space between said two arms, a pressing iron and means for heating it, a double ended lever 55 pivoted to said bifurcated arm and connected at one end to the pressing iron, the other end of the said lever being provided with adjustable means for regulating the pressure to be imparted to the iron, a work 60 feeding device, a driving shaft, and means for actuating the feeding device and the pressing iron independently of each other from the driving shaft as and for the purposes set forth.

HARRY BENSON CRANAGE.
